UNITED STATES PATENT OFFICE.

HENRY T. KROG, OF HUNTINGTON PARK, AND ALBERT F. HARTEL, OF LOS ANGELES, CALIFORNIA, ASSIGNEES TO A. J. BAYER COMPANY, A CORPORATION OF CALIFORNIA.

ELEVATOR-DOOR LOCK.

Application filed October 31, 1925. Serial No. 66,049.

To all whom it may concern:

Be it known that we, HENRY T. KROG and ALBERT F. HARTEL, citizens of the United States of America, and residents of Huntington Park, California, and Los Angeles, California, respectively, have invented certain new and useful Improvements in Elevator-Door Locks, of which the following is a specification.

10 Our invention relates to elevator door locks and more particularly for that class of doors known as elevator hatchways, i. e., those in which the door when closed is flush with the side walk or floor. The invention 15 contemplates a construction which will automatically unlock the door by the lifting of the elevator or hoist and will be automatically locked when the elevator recedes so that the same is out of contact with the 20 doors.

Referring to the accompanying drawings,

Fig. 1 is a perspective view of an open hatchway showing the doors opened and 25 having our invention applied thereto.

Fig. 2 is a detail view of the locking members, the same being shown in a locked position.

Fig. 3 is an enlarged view at right angles 30 to Fig. 2 and shows the locking members and their associated parts.

Fig. 4 is a section of a hatchway with the doors locked.

Fig. 5, like Fig. 4, is a section of a hatchway showing the doors closed but with the locking members in unlocked position.

Fig. 6 is a section of a hatchway like Figures 4 and 5, but showing the doors being opened by the elevator.

40 As shown in Fig. 1, 1 is a hatchway frame to which are hinged the doors 2 and 2^a. The elevator or hoist proper 3 has fixed to it an arched bow 4, which is the tripping or unlocking member for the lock and which also 45 acts as the door opener, as will subsequently be described. The lock consists of an L-shaped keeper 5 which has therein a perforation 6, said perforation having an outlet slot 7 which is narrower in width than the 50 perforation 6, all of which is shown in Figs. 3 to 6 inclusive. This locking member 5 is fixed to the door 2^a and is so positioned on the door that the bolt 8, which is fixed to

the other door 2, enters the opening 6 through the slot 7 when the doors are in a 55 closed position. The bolt 8 is rotatably mounted in the bracket 9 which is carried on the door 2, which door will open first and is therefore designated the "fast door" as distinguished from the door 2^a which will open 60 after the fast door and will be called the "slow door". The semicircular head 10 of the bolt 8 has a segment removed from the end thereof, which therefore is of such width that in one position it is no wider than the 65 slot 7 of the locking member 5, which it must enter to lock the doors. Mounted on the bolt 8 between the cut away head of the bolt and the bracket 9, and between the bracket and the nut 13 of the bolt, are washers 14 which construction allows the bolt to be turned easily in the bracket 9, thus minimizing the friction and allowing the bolt to be turned by the weight of the trip 11 which is attached between the projecting end of the 70 bracket to the bolt 8 by the set screw 15. The trip has on its end a right angle extension 12.

When the elevator is lifted, the bow 4 first comes in contact with the trip 11, lifting the 80 same until the upturned end 12 of the trip comes in contact with the underside of the fast door 2. The trip by its upward movement turns the bolt 8 so that the head 10 of the bolt is in such a position that it can pass 85 out of the slot 7 of the other locking member 5 on the further rise of the elevator. See Figure 5. In this position the door 2 can be and is raised further by the bow because the trip 11 is between the bow and the door and 90 in contact with both of them. With a further lift of the elevator the slow door 2^a comes in contact with the bow and both are raised together on the continuing lift of the elevator. When the elevator platform is lowered, the reverse takes place and the slow door 2^a is first to come in contact with the hatchway frame and have its downward 95 movement arrested. A further drop of the elevator allows the fast door 2 to close and 100 moves the bow out of contact with the trip 11, which drops by gravity, thus causing the bolt head 10 to be turned in the opening 6 of the other locking member, locking the doors in a closed position, where they can be only 105 unlocked from the underside of the doors.

Having thus described our invention what we claim as new and desire to secure by Letters Patent is:—

1. In a hatchway the combination of a pair of hinged doors, one having thereon a keeper with a perforation and a slot smaller than the perforation, the other door having mounted thereon a rotary bolt having one end of such a width that the same may enter the perforation of the keeper through the slot when in one position, and a weighted trip tending to move the bolt from such position.

2. In a hatchway the combination of hinged doors, one door having thereon a keeper containing a restricted opening, the other door having mounted thereon a bolt with a sector removed from its head and attached thereto a trip, with means in the hatchway for regulating the position of the bolt head within the keeper.

3. In a hatchway lock, the combination with a pair of hinged doors, one having

thereon a keeper having a perforation opening upwardly through a restricted slot, a bolt axially pivoted on the other door and having a portion adapted in one angular position of the bolt to enter the slot but of greater length than the width of the slot, a gravitational member influencing the bolt and tending to maintain it in the position in which it will not pass through the slot, said member having an upturned portion adapted in the unlocking position of the bolt to contact with the last named door, and means for successively lifting the gravitational member into contact with the door and simultaneously rotating the bolt to its unlocked position and to then raise the last named door and to thereafter lift the first named door.

In testimony whereof we hereunto affix our signatures.

HENRY T. KROG.
ALBERT F. HARTEL.
